W. P. Hutchinson.

UNITED STATES PATENT OFFICE

WILLIAM D. PHILIPS, OF BROOKLYN, NEW YORK.

AIR-WASHING APPARATUS.

1,296,315.

Specification of Letters Patent.

Patented Mar. 4, 1919.

Application filed June 15, 1917. Serial No. 174,915.

To all whom it may concern:

Be it known that I, WILLIAM D. PHILIPS, a citizen of the United States, and a resident of the borough of Brooklyn, county of 5 Kings, and State of New York, have invented a new and useful Improvement in Air-Washing Apparatus, of which the following is a full, clear, and exact description.

My invention relates to improvements in 10 air washing apparatus. Apparatus of this kind are generally alike in principle, that is the air to be washed of its impurities is drawn or forced through a spray or sheets of water so that the sediment and various 15 impurities in the air will be caught and washed down by the water, and the purified air will be drawn off and delivered at a desired point. Many devices of this character have been used, and most of 20 them have rather elaborate and somewhat expensive means of producing the desired spray, and many of the forms of spraying devices used are unsatisfactory and of such a nature that impurities of the air which 25 can be picked up by water are not always separated. The object of my invention is especially to provide a very simple and inexpensive means of forming the wash water into a spray sufficiently fine to thoroughly 30 wash the air, and to prevent the water from being withdrawn with the air. Except for the form of picking up the water and throwing it into a spray, my apparatus can be of any usual conventional or preferred kind. 35 For a spraying apparatus I use a series of rotating members, any desired number being used, which will dip into the water which is contained in the casing, and by centrifugal or scooping action, or both, I pick 40 the water up and throw it from the rotating members in the form of a spray. It will be seen that this arrangement can be of a very simple nature, the essential things being to have a rotatable shaft contained in 45 the water holding casing, and to provide members on the shaft which by their rotation will pick up and throw off the water in spray form. It is desirable to use a relatively large number of such members, and 50 I have found by experiment that by having the rotating members in the form of thin

disks with serrated edges, and with shallow buckets on opposite sides of each disk, at points coincident with the serrations, I get an excellent result, but my invention is not 55 confined to the particular form of disk, though I claim this as a feature of the invention. All of which will be more clearly understood from the description which follows.

Reference is to be had to the accompanying drawings forming a part of this specification, in which similar reference characters indicate corresponding parts in all 60 the views.

Figure 1 is a sectional plan of a common form of air washing apparatus provided with my improved spraying means.

Fig. 2 is a vertical longitudinal section of the apparatus.

Fig. 3 is a broken detail elevation of a section of one of the disks, and

Fig. 4 is a detail cross section of a part of one of said rotary disks or spraying members.

In order that the apparatus can be clearly understood, I have shown it applied to a somewhat common form of apparatus in which the casing 10 may be of any approved size, and is provided at one end with an air 80 inlet 11 which as usual can connect by means of a pipe with any source of air supply. At the opposite end the casing is shown reduced as at 12 and connected by a pipe 13 with an exhauster 14 having an outlet 15 which 85 can as usual have a pipe connection discharging at a desired point. So far as my invention is concerned it will be seen that the air can be either drawn through or blown through the casing, but the common 90 method is to draw it through by means of an exhauster.

It is customary also to heat the water so that it can be more volatile and more easily sprayed, and to this end I have shown a steam pipe 15 entering the casing and lying at the bottom in the form of a coil 16. I have also shown a water supply pipe 17 and a drain pipe 18. Between the spraying means and the discharge end of the casing 100 are baffles 19 which permit the air to be withdrawn but which prevent the water

from passing out to the washed air. All the above apparatus is somewhat conventional and can be varied to suit different circumstances.

5 The spraying apparatus is mounted on a rotatable shaft 20 which extends transversely from the casing 10 and can be rotated by any suitable means, the shaft as shown having a pulley 21 by which it can 10 be driven. On this shaft are rotatable members which dip into the water in the bottom of the casing, pick it up and throw it off in the form of spray. It will be evident that 15 various forms of apparatus can be used for this purpose, but in practice I have found the best means to consist of a rotating disk 22 secured to the shaft 20 and having serrations 23 at the edges which are generally radial. Near the inner end of each serration 20 is formed a rather shallow bucket 24 which can be conveniently produced by doubling over the metal or material at the inner end of one serration and allowing the edge of the doubled over portion to taper gradually 25 to the outer part of the next serration as shown clearly in Figs. 3 and 4. These buckets are formed alternately on opposite sides of the disk, and it will be seen that this arrangement produces a shallow bucket of a 30 generally conical shape, closed at its inner end and opening outwardly and gradually so that as the member 22 rotates the water is picked up by the buckets and the centrifugal action expels it, but instead of expelling 35 it in a jet form, the contour of the buckets opening gradually as they do and along a curved line, causes the water to be broken up and formed into a spray. This action is also facilitated by the abrupt edges of the 40 serrations 23, and in fact the disk itself picks up the water on its sides and throws it off by centrifugal action, and the buckets intercept the water thus thrown off by the sides of the disk and breaks it up into spray 45 form.

It will be seen that this arrangement makes an unusually simple form of spraying apparatus, and I have found by actual use that it is a very efficient spraying means.

50 The rotating members can be made of any approved size, according to the size of the apparatus used, and they should be arranged as shown so that their lower edges will dip into the water.

55 In practice the water picked up by the rotating members 22 fills the casing 10 with spray, and the air is drawn through this spray, washed of its impurities, and discharged at the desired point.

60 I wish it distinctly understood that my invention lies in the spraying means consisting of rotating members dipping into the water and discharging it centrifugally; that I prefer the form of rotating members shown,

although the invention is not limited to this form, and that the spraying apparatus described can be applied to any desired form of casing in which water can be held so that it may be picked up by the rotating members.

70 It will be further noticed that the flaring buckets 24 have one edge elongated and gradually merging into the plane of the disk 22 so that these buckets instead of discharging the water in a jet, throw it out in a 75 spray, and further that they act as baffles so that the water following the general plane of the disk bodies, strikes the flaring buckets and is broken up and forced out laterally as well as radially with reference to 80 the disks, thus making a fine spray.

85 From the foregoing description it will be clearly understood that not only can the form of the rotating members forming the spraying device be changed without affecting the invention, but also that the number of these rotating members will vary with the capacity of the apparatus, and that any number of rotating members can be used from one up and that if more than one is 90 used they can be spaced apart as occasion requires. It will also be evident that while I have shown the spraying device arranged transversely to the flow of air through the casing, that this is not material, and that 95 the spraying device can be arranged at any angle or position with relation to the air current so long as it dips into the water body and expels the water in the form of a spray.

100 I claim:—

1. An apparatus of the kind described comprising a water containing casing, means for passing air therethrough, a rotatable shaft extending through the casing above the water, and disks spaced apart on the shaft and dipping into the water, each disk having near its periphery and on the sides tangentially arranged buckets of generally conical shape with widely flaring mouths. 110

2. A rotatable spraying device comprising disks spaced apart and having buckets on the sides thereof.

3. A rotatable spraying device comprising disks spaced apart and having buckets on opposite sides of each disk member. 115

4. A rotatable spraying device comprising disk members spaced apart and provided with buckets having flaring mouths.

5. In an apparatus of the kind described, the spraying disk having flaring buckets on opposite sides thereof. 120

6. In an apparatus of the kind described, the spraying disk having a serrated edge and buckets formed between the serrations. 125

7. In a structure of the kind described, the spraying disk having serrated edges and flaring buckets between the serrations

and on opposite sides of the disk the buckets
alternating.

8. An apparatus of the kind described
comprising a water containing casing hav-
5 ing means for passing air therethrough, and
a rotatable spraying device comprising disks
spaced apart and arranged to dip in the

water, each disk having baffles on the sides
in the form of buckets.

WILLIAM D. PHILIPS.
